United States Patent

Des. 235,855
Patented July 15, 1975

235,855

LINEAR DISTANCE MEASURING DEVICE

Nicholas G. Polydoris, Kenilworth, and Burnell J. Wollar,
Barrington, Ill., assignors to ENM Company, Chicago,
Ill.

Continuation-in-part of design application Ser. No.
297,235, Oct. 13, 1972, now Patent No. 232,349.
This application Feb. 25, 1974, Ser. No. 445,669

Term of patent 14 years

Int. CL D10—04

U.S. CL. D10—70

FIG. 1 is a front elevational view of a linear distance measuring device, showing our new design;

FIG. 2 is a left-side elevational view thereof;

FIG. 3 is a right-side elevational view thereof;

FIG. 4 is a top plan view thereof;

FIG. 5 is a bottom plan view thereof; and

FIG. 6 is a rear elevational view thereof.

This application is a continuation-in-part of applicants' copending application Ser. No. 297,235, filed Oct. 13, 1972, and now Pat. No. D. 232,349.

We claim:

The ornamental design for a linear distance measuring device, substantially as shown and described.
